US00D739396S

(12) **United States Design Patent**
Wheatley et al.

(10) **Patent No.:** **US D739,396 S**
(45) **Date of Patent:** **** Sep. 22, 2015**

(54) **FRictional HOLDING PAD WITH
INCLINED GRIP**

(71) Applicant: **American Covers, Inc.**, Draper, UT (US)

(72) Inventors: **Alan J. Wheatley**, Draper, UT (US); **Bryce Craig**, Alpine, UT (US)

(73) Assignee: **American Covers, Inc.**, Draper, UT (US)

(**) Term: **14 Years**

(21) Appl. No.: **29/479,892**

(22) Filed: **Jan. 21, 2014**

Related U.S. Application Data

(63) Continuation of application No. 13/940,074, filed on Jul. 11, 2013, now Pat. No. 8,851,349, which is a continuation of application No. 12/987,662, filed on Jan. 10, 2011, now Pat. No. 8,490,846.

(57) **CLAIM**

The ornamental design for the frictional holding pad with inclined grip, as shown and described.

DESCRIPTION

FIG. 1 is a perspective view of the frictional holding pad with inclined grip in accordance with our invention;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines shown in FIGS. 1-4 and 7 are for illustrative purposes only and form no part of the claimed design.

1 Claim, 3 Drawing Sheets
